DIAMOND TOOL ASSEMBLY

Joseph Loeey, Jr., Euclid, Ohio

Application November 29, 1948, Serial No. 62,449

1 Claim. (Cl. 125—11)

1

The present invention relates to an improved assembly of diamond tool for dressing grinding wheels.

As is of course well known to those who are familiar with the art to which the present invention relates, a diamond tool is moved at intervals into position for operative engagement with a grinding wheel for dressing the same; and it has been the usual practice in the past to depend upon the workman to turn the diamond tool at certain intervals in order to always present a new sharp point and to prevent the diamond from wearing unevenly and thereby lengthen the life of the same. Experience has shown, however, that the workmen fail to make such adjustments with the necessary regularity and to the proper degree if at all.

It is therefore the object of the present invention to devise an assembly in which the diamond tool may be moved to position for operative engagement with the grinding wheel and at the same time be automatically turned slightly so as to always present a new sharp point of the diamond to the wheel and prevent uneven wear of the diamond.

A more specific object is to devise an assembly with hydraulic means for moving the diamond tool into position for operative engagement with the grinding wheel and for simultaneously turning the diamond tool slightly so as to always present a new point of the diamond to the grinding wheel and thus ensure against uneven wear of the diamond.

A still more specific object of my present invention is to devise a piston and cylinder assembly in which the diamond tool may be mounted upon either the piston or the cylinder and in which there may be employed hydraulic means for effecting relative longitudinal movement between the piston and cylinder for moving the diamond tool into and out of position for operative engagement with the grinding wheel and for simultaneously turning the diamond tool slightly during either its movement towards or away from the grinding wheel for the purpose of ensuring against uneven wear of the diamond and so as to always present a new point of the diamond to the grinding wheel.

Other objects will appear from the following description and claim when considered together with the accompanying drawing.

Fig. 1 is a perspective view of my present improved device;

Fig. 2 is a side elevation of the same, with part broken away so as to show the relation of the several elements;

2

Fig. 3 is an end elevation thereof; and

Fig. 4 is a distended view of some of the parts in perspective.

It is to be understood that the present form of disclosure is merely for the purpose of illustration and that there might be devised various modifications thereof without departing from the spirit of my invention as herein set forth and claimed.

My present assembly may be mounted upon or attached to any type of grinder by means of the rearwardly extending shank portion 2 of the cylinder member 1. The cylinder member 1 has a restricted cylindrical portion 3 for accommodation of the shaft 4 of the plunger or piston 5 which is of larger diameter and is adapted to be received by the correspondingly larger cylindrical portion 6 of the cylinder member 1. The cylindrical portion 3 is provided with the annular groove 7 for an oil seal.

In the forward end of the shaft 4 there is mounted the diamond tool 8 with the diamond point 9; and this tool may be removably mounted by means of the screw-threaded engagement indicated at 10.

At diametrically opposite points of the cylinder member 1 there are attached by means of screw-threaded engagement the two oil tubes 11 and 12, one of which has constant communication with the annular groove 13 provided about the perimeter of the plunger or piston 5, while the other tube 12 has communication with the chamber 6 at the forward side of the piston 5. Upon the edge of the piston 5, the groove 13 may have a plurality of inclined straight ducts or grooves 14 leading therefrom so as to open into the cylindrical chamber 6 in directions towards spaced points about the end of the cylinder 6.

The purpose of these annular and inclined grooves is to introduce oil under pressure therethrough so as to cause the same to be impinged in an inclined manner against the knurled groove 15 in the end of the chamber 6 and thereby give the piston a compound movement, that is simultaneously along the cylinder and rotatively therein. From the groove 15 the ducts 15a will permit the oil to pass into the central well 15b so as to prevent any interference of this oil with the turning of the piston 5. Thus, during the initial period of operation, the jets of oil from the ducts 14 may be impinged effectively against the bottom of the groove 15 so as to effect turning of the piston 5. This turning of the piston may be provided for either the forward or rearward movement of the same and the ducts or grooves 14 may be arranged accordingly. In either case,

50

55

hydraulic means may be provided upon the other side of the piston 5 for moving the same in the opposite direction, as herein indicated. It may be that the return movement of the piston 5 will have slight rotary movement as a result of the oil being forced back through the grooves or ducts 14.

The depth of the cylindrical chamber 6 will be sufficient to permit necessary movement of the diamond tool into and out of proper position for operative engagement with the grinding wheel; and the groove 13 will be so positioned and of such width that it will always be in communication with the inner end of the tube 12 so as to always permit introduction of the oil thereto and therefrom as may be desired in accordance with the operation herein set forth.

In actual operation of this device, suitable pressure will be supplied to either of the tubes 11 and 12, as may be desired to move the diamond tool out of operative position with respect to the grinding wheel or into such position. For this purpose, the tubes 11 and 12 may have an oil pump 16 which may be connected through the hand-operated valve 17 with either of the tubes 11 and 12, as may be required, by merely manipulating this valve. That is to say, by means of the valve 17 the pump pressure may be applied to the tube 12 for moving the piston forwardly and at the same time turning it slightly so as to present a fresh point of the diamond for dressing the grinding wheel. So long as the valve 17 is held in that position, the diamond tool will be held in such dressing position; and thus it may be said that the diamond tool is moved forwardly, turned and held in such operative position by a unitary hydraulic means. It is to be understood that the hydraulic pressure will force the piston to the end of the chamber 6 and hold it thereagainst. Then, upon completion of the dressing operation, the valve 17 may be adjusted so as to apply the oil pressure to the other tube 11 and its corresponding side of the piston 5, while at the same time relieving the pressure upon the first side of the piston, so as to thereby move the piston in the reverse direction and permit return of the oil through the first oil tube 12 to the oil reservoir from which the oil supply is obtained for such operation.

It is to be understood, of course, that the diamond tool will occupy withdrawn position during the grinding operation and that the diamond

tool will be moved into dressing position whenever desired during those periods when there is no grinding taking place. It will be understood also that for the purpose of moving the diamond tool into and out of operative position with respect to the grinding wheel, only a slight extent of movement is necessary. Likewise, it is most desirable that each turning movement of the diamond tool be of only very slight extent.

This invention may be embodied as part of a machine which has a hydraulically operated dresser and in which there is already provided an oil pump and in which there may be automatic operation of the valve instead of the hand manipulation above described.

What I claim is:

In a device of the class described, the combination of a cylinder, a piston having straight-line movement within said cylinder, a dressing tool carried by said piston, said cylinder having supply connections for application of hydraulic pressure to either end of said piston chamber for moving said piston either forwardly or rearwardly therealong, a valve in said supply connections for determining the application of the hydraulic pressure individually to one or the other end of said piston, hydraulic means including an annular duct provided in said piston and auxiliary ducts inclined therefrom towards one end of said cylinder and operative only during straight-line movement of said piston for thereby effecting simultaneously a rotative movement of said piston and dressing tool predominantly in only one direction and for holding the same in such changed position with relation to the work.
